SYNCHRONOUS ELECTRIC ALARM CLOCK

Arthur B. Poole, Harwinton, Conn.

Application June 2, 1945, Serial No. 597,202

7 Claims. (Cl. 58—19)

1

The present invention relates to improvements in electric alarm clocks and relates more particularly to alarm clocks which are propelled by a synchronous electric motor and which have an alarm mechanism of a type wherein a make-and-break circuit is employed for controlling the alarm, in contradistinction to the type of electric alarm wherein the alternations of the current supply are utilized to govern the vibration-frequency of the alarm.

One of the objects of the present invention is to provide a superior synchronous electric alarm clock of the character referred to which will clearly sound an alarm and which has its electric alarm-mechanism so constructed and arranged as to be reliable in use and substantially free from the likelihood of accidental derangement.

Another object of the present invention is to provide a superior electric alarm clock of the character referred to which will provide a clear audible signal and which may be rendered operative or inoperative in a simple, reliable and convenient manner.

A further object of the present invention is to provide a simple, reliable and effective synchronous electric alarm clock in which is embodied a make-and-break contact for controlling the energization of an electromagnet and so constructed and arranged that the relatively-high rate of flux-change in the said electromagnet will not deleteriously affect the clear sounding of an audible signal at a slower beat-frequency.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a schematic perspective view illustrating a synchronous electric alarm clock embodying the present invention and showing the alarm-mechanism in its inoperative position;

Fig. 2 is a longitudinal sectional view taken through the longitudinal axis of the alarm-set shaft but on a larger scale;

Fig. 3 is a schematic perspective view similar to Fig. 1 but less comprehensive than the same and showing the alarm-control cam turned into position to release the alarm-mechanism; and

Fig. 4 is a view corresponding to Fig. 2 but showing the alarm-mechanism in its released position.

The particular synchronous electric alarm

clock chosen for illustration in the accompanying drawings for purposes of making clear a preferred form of the present invention, includes a synchronous electric motor 10 which may be of any approved type and which requires no detailed description herein other than to note that it is provided with a drive-shaft 11, which rotates synchronously, i. e., at a fixed ratio with respect to the frequency of the alternating current supplied to the said motor, all in a manner well understood in the art.

The drive-shaft 11 above referred to has rigidly attached to it a drive-pinion 12 which meshes into and drives a gear-wheel 13. The said gear-wheel 13 is rigidly mounted at the rear end of a shaft 14, which latter rigidly carries at its forward end a pinion 15. The pinion 15 in turn meshes into and drives a gear-wheel 16 rigidly mounted on the rear end of a shaft 17. At its forward end, the shaft 17 has rigidly mounted upon it a pinion 18 which meshes into and drives an hour-wheel 19.

The hour-wheel 19 above referred to is rigidly mounted upon the inner end of an hour-sleeve 20 which rigidly carries at its outer end an hour-hand 21.

Extending through the hour-sleeve 20 with freedom for rotation therein, is a minute-sleeve 22 carrying at its forward end a minute-hand 23. At its rear or inner end the said minute-sleeve projects beyond the hour-wheel 19 into position where it may be driven at one R. P. H. by any suitable gearing (not shown) in a manner well known in the art.

Extending through the minute-sleeve 22 in turn and with freedom for relative rotation therein, is a seconds-arbor 24 having its forward end projecting beyond the forward end of the minute-sleeve 22 and carrying a seconds-pointer 25. The rear or inner end of the said seconds-arbor 24 extends beyond the inner end of the minute-sleeve 22 into position to be driven at one R. P. M. by any suitable gearing (not shown) in a manner well understood in the art.

The hour-wheel 19 above referred to meshes into and drives a pinion 26 which is mounted upon a shaft 27 and which, in turn, meshes into and drives an alarm-control wheel 28. The said wheel 28 is mounted with freedom for both rotation and axial movement upon an alarm-set shaft 29 adjacent the forward end of a sleeve 30 which, in turn, is mounted with freedom for both rotation and axial sliding movement upon the said alarm-set shaft 29. The said shaft 29 has rigidly mounted upon its forward end an alarm-set

pointer 31 and has rigidly mounted upon its rear end a knurled finger-button 32, by means of which the said shaft 29 may be turned, for purposes as will hereinafter appear.

Located forwardly of and rigidly secured to the alarm-control wheel 28 is a sleeve-like alarm-control cam 33 having a drop-off notch 34 and rotating at one-twelfth R. P. H. (once in each twelve hours) in consonance with the hour-wheel 19. Coacting with the forward edge of the sleeve-like alarm-control cam 33, is an alarm-control finger 35 which is rigidly mounted upon the shaft 29 and is adapted to enter the drop-off notch 34 of the alarm-control cam 33, under conditions as will hereinafter appear.

Adjacent its rear or inner end, the sleeve 30 is formed with an annular flange 36, the rear face of which is adapted to engage with the forward face of an insulating-plate 37. The said insulating-plate is formed with an aperture 38 through which freely extends a portion of the sleeve 30, as is clearly shown in Figs. 2 and 4. The said aperture 38 is of sufficient size to clear the adjacent portion of the sleeve 30.

Pressing forwardly upon the rear end of the sleeve 30 is a helical spring 39 encircling the adjacent portion of the alarm-set shaft 29 and seated at its rear end against a collar 40 rigidly mounted upon the alarm-set shaft 29 at a point spaced rearwardly of the insulating-plate 37.

The insulating-plate 37 is secured to the lower end of a spring-like mounting-arm 41 which is secured at its upper end to an insulating-plate 42. The said mounting-arm 41 is formed of spring metal and carries at a point above the insulating-plate 37, a movable contact 44 extending forwardly from the said mounting-arm and adapted to engage with and disengage from a normally-stationary complementary contact 45 arranged coaxially with respect to the contact 44 and carried by a bracket 46. The spring-like arm 41 is so tensioned as to tend to engage the movable contact 44 with the normally stationary contact 45.

Mounted adjacent the insulating-plate 37 is a plate-like armature 47 formed of soft iron or other suitable magnetic material and secured to the upper end of a spring-like mounting-arm 48 which latter has its lower end in turn mounted upon a stationary bracket 49. Secured to and extending upwardly from the armature 47 is a striker-arm 50 preferably formed of resilient material and carrying at its upper end a striker-head 51. The said striker-head is adapted to impinge against the periphery of a stationary bell 52 carried by a bell-bracket 53.

The armature 47 above referred to also has secured to it a contact-actuating arm 54 projecting laterally therefrom into a position in front of the insulating-plate 37 for the purpose of moving the same rearwardly in a manner as will hereinafter appear.

Mounted to the rear of the armature 47 is an alarm-operating electromagnet 55 having a pole-piece 56 projecting into proximity to the rear face of the armature 47 for purposes of attracting the said armature under circumstances as will hereinafter be described. The spring-like mounting-arm 48 is so tensioned as to tend to hold the rear face of the armature 47 in a position spaced forwardly of the forward end of the pole-piece 56 of the electromagnet 55 though the said mounting-arm is sufficiently flexible to permit the said armature to be pulled rearwardly by the said electromagnet to cause the striker-head 51 to engage with the bell 52.

One terminal lead of the electromagnet 55 is connected by means of a wire 57 to the bracket 46 and hence also to the normally-stationary contact 45. The remaining terminal of the electromagnet 55 is connected by means of a wire 58 to a supply-wire 59. The supply-wire 59 is complemented by a second supply-wire 60 which latter is connected by means of a wire 61 to the mounting-arm 41 and hence also to the movable contact 44. The supply-wire 59 is connected by means of a wire 62 to one terminal of the synchronous electric motor 10, while the remaining terminal of the said motor is connected by means of a wire 63 to the supply-wire 60.

From the foregoing it will be seen that the contacts 44 and 45 and the electromagnet 55 are connected in series with each other between the supply-wires 59 and 60. It will also be seen that the connection of the supply-wires 59 and 60 to a source of alternating current such, for instance, as a 60-cycle 110-volt source will energize said synchronous electric motor 10. The circuit of the electromagnet 55 will also be energized provided only that the contact 44 is in engagement 25 with the contact 45.

Operation

For purposes of description let it be assumed that the supply-wires 59 and 60 are connected to a suitable source of alternating current such, for instance as 60-cycle 110-volt alternating current. Let it further be assumed that the alarm-control finger 35 of the alarm-set shaft 29 is engaged with the edge of the alarm-control cam 33 35 of the alarm-control wheel 28.

Under these conditions the synchronous electric motor 10 will be energized and will drive the hour-hand 21 and the minute-hand 23 and seconds-pointer 25 to indicate the time. Also under 40 the conditions just referred to, the unit comprising the alarm-control wheel 28 and sleeve 30 will also be held rearwardly against the tension of the spring 39. Thus the rear face of the flange 36 of the sleeve 30 will be engaged with the forward face of the insulating-plate 37 thus forcing the same rearwardly by rearwardly flexing the mounting-arm 41 to maintain the movable contact 44 out of engagement with the stationary contact 45, as is especially well shown in Fig. 2.

Under the conditions above described the contact 44 will be out of engagement with the contact 45 so that the alarm-operating electromagnet 55 will not be energized and hence the alarm mechanism will be inoperative.

Now as the hour-wheel 19 turns as time goes on, it will turn the alarm-control wheel 28 and thus at a predetermined time bring the drop-off notch 34 of the sleeve-like alarm-control cam 33 into registry with the alarm-control finger 35 on the alarm-set shaft 29. The alarm-set staff 29 will, meanwhile, be held against rotation with the wheel 28 by any suitable friction-means (not shown) as is common in the art of alarm clocks.

As soon as the drop-off notch 34 is brought 65 into registry with the alarm-control finger 35 as above described, the spring 39 will assert itself and force the unit comprising the sleeve 30 and alarm-control wheel 28 forwardly to thus similarly shift the flange 36 of the said sleeve. As the said flange 36 moves forwardly as described, the unit comprising the insulating-plate 37, the mounting-arm 41 and contact 44 will swing forwardly until the said contact 44 is brought into engagement with its complementary contact 45.

As soon as the said contact 44 engages with the

contact 45, the circuit through the alarm-operating electromagnet 55 will be closed with the result that the said electromagnet will draw the armature 47 rearwardly. The rearward movement of the armature 47 will cause the striker-head 51 to engage with the bell 52 and at the same time will cause the outer end of the contact-actuating arm 54 to force the insulating-plate 37 rearwardly to thus move the contact 44 out of engagement with its complemental contact 45 to thereby break the circuit through the electromagnet 55. As soon as the electromagnet 55 is deprived of energy as just described, it will permit the flexible mounting-arm 48 to swing the armature 47 forwardly together with the parts carried by the said armature and thus permit the tension of the mounting-arm 41 to re-engage the contact 44 with the contact 45 to again repeat the cycle just described.

When it is desired to manually shut off the alarm, an alarm-shutoff latch 64 may be swung over from the position in which it is shown by full lines in Fig. 1 into engagement with the insulating-plate 37 as indicated by broken lines. The swinging of the latch 64, as described, will force the insulating-plate 37 rearwardly and hold the same in such position wherein the movable contact 44 is held out of engagement with the contact 45.

The contact-actuating arm 54 by reason of its one-way engagement with the insulating-plate 37 provides a contact-actuating means which serves to move the contact 44 out of engagement with the contact 45 when the armature 47 is attracted by the electromagnet 55 but which permits the said armature to move away from the electromagnet without the said arm 54 itself acting to move the contact 44 forwardly. The operative connection provided by the arm 54 may thus be viewed as a "one-way" or "lost-motion" connection.

By the character of the connection between the armature 47 and the contact 44, it is feasible to permit the contact 44 to remain in engagement with the contact 45 until the armature 47 has almost completed its movement toward the electromagnet 55 to thus insure that the clear and distinct as well as relatively powerful alarm will be sounded despite the employment of alternating current for the energization of the electromagnet 55. In some instances it may be desirable to omit the bell 52 as well as the striker-arm 50 and striker-head 51 and rely upon the sound which may be produced by having the armature 47 itself engage with the pole-piece 56 of the electromagnet 55.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An electric alarm clock, including in combination: a synchronous electric motor; time-indicating means driven by the said synchronous electric motor; a first-contact; a second-contact engageable with and disengageable from the said first-contact; spring-means urging the said second-contact into engagement with the said first-contact; an alarm-operating electromagnet; a circuit electrically connecting the said electro-

magnet, the said first-contact and the said second-contact in series; an armature operatively associated with the said electromagnet in position to be attracted thereby; contact-actuating means operatively interposed between the said armature and the said second-contact and constructed and arranged to move the said second-contact out of engagement with the said first-contact when the said armature is attracted by the said electromagnet and to permit the said armature to move away from the said electromagnet without the said means itself moving the said second-contact into engagement with the said first-contact; and alarm-control means associated with the said contact-members and driven by the said synchronous electric motor and constructed and arranged to control the flow of current between the said contact-members and hence through the said alarm-operating electromagnet.

2. An electric alarm clock as set forth in claim 1 and in which the contact-actuating means specified, includes a resilient member carried by the said armature.

3. An electric alarm clock, including in combination: a synchronous electric motor; time-indicating means driven by the said synchronous electric motor; a first-contact; a second-contact engageable with and disengageable from the said first-contact; spring-means urging the said second-contact into engagement with the said first-contact; an alarm-operating electromagnet; a circuit electrically connecting the said electromagnet, the said first-contact and the said second-contact in series; an armature operatively associated with the said electromagnet in position to be attracted thereby; contact-actuating means operatively interposed between the said armature and the said second-contact and constructed and arranged to move the said second-contact out of engagement with the said first-contact when the said armature is attracted by the said electromagnet and to permit the said armature to move away from the said electromagnet without the said means itself moving the said second-contact into engagement with the said first-contact; and alarm-control means driven by the said synchronous electric motor and including cam-means constructed and arranged to also move the said second-contact out of engagement with the said first-contact, and spring-means yieldingly opposing the said action of the said cam-means.

4. An electric alarm clock, including in combination: a synchronous electric motor; time-indicating means driven by the said synchronous electric motor; a first-contact; movable contact-carrying means having an abutment; a second-contact carried by the said contact-carrying means and engageable with and disengageable from the said first-contact; spring-means urging the said contact-carrying means in a direction to cause the said second-contact to engage with the said first-contact; an alarm-operating electromagnet; a circuit electrically connecting the said electromagnet, the said first-contact and the said second-contact in series; an armature operatively associated with the said electromagnet in position to be attracted thereby; a contact-actuating abutment carried by the said armature and engageable with the abutment of the said contact-carrying means to move the said second-contact out of engagement with the said first-contact when the said armature is attracted by the said electromagnet, the said contact-actuating abutment being movable away from the abutment of

the said contact-carrying means to permit the said armature to move away from the said electromagnet independently of the movement of the said contact-carrying means; and alarm-control means associated with the said contact-members and driven by the said synchronous electric motor and constructed and arranged to control the flow of current between the said contact-members and hence through the said alarm-operating electromagnet.

5. An electric alarm clock as set forth in claim 4 and in which is included a resilient-member; and in which the contact-actuating abutment is carried by the said resilient-member which itself is carried by the said armature.

6. An electric alarm clock, including in combination: a synchronous electric motor; time-indicating means driven by the said synchronous electric motor; a first contact; a movable contact-carrying means having an abutment; a second-contact carried by the said contact-carrying means and engageable with and disengageable from the said first-contact; spring-means urging the said contact-carrying means in a direction to cause the said second-contact to engage with the said first-contact; an alarm-operating electromagnet; a circuit electrically connecting the said electromagnet, the said first-contact and the said second-contact in series; an armature operatively associated with the said electromagnet in position to be attracted thereby; a contact-actuating abutment carried by the said armature and engageable with the abutment of the said contact-carrying means to move the said second-contact out of engagement with the said first-contact when the said armature is attracted by the said electromagnet, the said contact-actuating abutment being movable away from the abutment of the said contact-carrying means to permit the said armature to move away from the said electromagnet independently of the movement of the said contact-carrying means; and alarm-control means driven by the said synchronous electric motor and including cam-means constructed and arranged to move the said contact-carrying means in a direction to disengage the said second-contact from the said first-contact, and spring-means yieldingly opposing the said action of the said cam-means.

7. An electric alarm clock, including in com- 50

bination: a synchronous electric motor; time-indicating means driven by the said synchronous electric motor; an alarm-set shaft; a cam-member rigid with the said alarm-set shaft; a cam-unit coacting with the said cam-member and rotating around the said alarm-set shaft, the said cam-unit being axially movable with respect to the said shaft by its coaction with the said cam-member, the said cam-unit also being operatively connected to the said synchronous electric motor to be rotated thereby; a first-contact; a second-contact engageable with and disengageable from the said first-contact; movable contact-carrying means having an abutment and carrying the said second-contact; the said contact-carrying means having a portion movable by the said rotary cam-unit in a direction to move the said second-contact out of engagement with the said first-contact; spring-means urging the said contact-carrying means in a direction to cause the said second-contact to engage with the said first-contact; an alarm-operating electromagnet; a circuit electrically connecting the said electromagnet, the said first-contact and the said second-contact in series; an armature operatively associated with the said electromagnet in position to be attracted thereby; a contact-actuating abutment carried by the said armature and engageable with the abutment of the said contact-carrying means to move the said second-contact out of engagement with the said first-contact when the said armature is attracted by the said electromagnet, the said contact-actuating abutment being movable away from the abutment of the said contact-carrying means to permit the said armature to move away from the said electromagnet independently of the movement of the said contact-carrying means and of the said rotary cam-unit.
